TABLE

Peter Hvidt and Orla Mølgaard Nielsen, Copenhagen,
Denmark, assignors to John Stuart Inc., New York,
N. Y., a corporation of New York

Application June 17, 1953, Serial No. 25,546

Term of patent 14 years

(Cl. D33—14)

FIG. 1.

FIG. 2.

FIG. 3.

Fig. 1 is a perspective view of a table showing our new design;

Fig. 2 is a side elevational view of the table of Fig. 1, but with the legs being broken away for convenience of illustration; and

Fig. 3 is a top plan view of the table of Figs. 1 and 2.

The dominant feature of the design resides in the portion shown in full lines, the design being characterized by three peripheral arcs of equal radius of curvature, one arc being concave and the other two being convex.

We claim:

The ornamental design for a table, as shown and described.
